(57) **CLAIM**

The ornamental design for a physical therapy vest, as shown and described.

DESCRIPTION

FIG. 1 is a left perspective view of a physical therapy vest;

FIG. 2 is a right perspective view of the vest of FIG. 1;

FIG. 3 is a front view of the vest of FIG. 1;

FIG. 4 is a rear view of the vest of FIG. 1;

FIG. 5 is a right side view of the vest of FIG. 1, the opposing side being the mirror image thereof;

FIG. 6 is a top end view of the vest of FIG. 1;

FIG. 7 is a bottom end view of the vest of FIG. 1;

FIG. 8 is a front view of another alternative embodiment of a physical therapy vest;

FIG. 9 is a rear view of the vest of FIG. 8;

FIG. 10 is a right side view of the vest of FIG. 8; the opposing left side view being the mirror image thereof; and,

FIG. 11 is a top end view of the vest of FIG. 8.

The left perspective view, front view, and bottom end view of the vest of FIG. 8 are shown in FIGS. 1, 3, and 7 respectively, identified above.

The phantom, broken lines shown are shown for environmental purposes only and form no part of the claimed design.
